METHOD OF FABRICATING BLOWER WHEELS

Gerald L. Schwarz, Cleveland, Ohio, assignor to
Air Controls, Inc., Cleveland, Ohio, a corpora-
tion

Application July 12, 1946, Serial No. 683,089

4 Claims. (Cl. 29—156.8)

1

My invention relates to blowers and methods of fabricating impellers therefor.

An object of my invention is to provide an improved, less expensive blower wheel construction.

A further object is to provide an improved method of making blower wheels or impellers.

Still another object of the invention is to fabricate blower wheels from sheet metal stock by punching and assembling formed sheet metal pieces.

Other and further objects, features and advantages of the invention will become apparent as the description proceeds.

In carrying out my invention in accordance with a preferred form thereof, strips of sheet metal or long, narrow pieces of other sheet material are bent so as to have a curved cross-section suitable for blower vanes. A pair of strips of sheet metal is passed through a punch press to form rabbets or arcuate slots therein which are open along one edge of the strip. The vanes are then dropped into the slots, preferably with the rabbeted strips spaced from the ends of the vanes, whereupon the strips are bent within their planes so as to close the slots and secure the vanes by holding and embracing the portion of the vane passing through the strip. Preferably, the closing of the slots is performed by a suitable type of bending device so that the strip is curved to lie along the circumference of a circle and the strip length is made such that the ends meet and may be joined by welding or other fusion process to form complete circular blower wheels or impellers.

The end rings formed by the bent rabbeted strips are secured to radial or diagonal spokes carried by a hub or shaft mounted in a suitable housing such as in conventional, centrifugal type blowers.

A better understanding of the invention will be afforded by the following detailed description, considered in conjunction with the accompanying drawing, in which

Fig. 1 is a perspective view of a completed blower with a portion thereof broken away, representing an embodiment of my invention;

Fig. 2 is a fragmentary view of a length of ring-forming strip showing a vane holding rabbet or arcuate slot before it has been closed by bending the strip;

Fig. 3 is a view corresponding to Fig. 2, illustrating the length of strip after the slot has been closed by bending the strip and showing the cross section of the portion of a vane embraced within the strip;

2

Fig. 4 is a perspective view of one of the vanes consisting of a bent, narrow sheet of material such as metal;

Fig. 5 is a schematic view representing in perspective a punch press which may be employed for rabbetting the ring-forming strip;

Fig. 6 is a longitudinal, medial, sectional view of a blower wheel constructed in accordance with my invention and fragmentarily representing a portion of the housing;

Fig. 7 is a schematic diagram of the ring-forming strip-bending machine; and

Fig. 8 is a fragmentary end view of the bent strip showing the manner of joining the ends to form a ring.

Like reference characters are utilized throughout the drawing to designate like parts.

As illustrated in Fig. 1, blower wheels constructed in accordance with my invention are adapted to be used in centrifugal blowers of the type having a housing 11 with air-inlet throats 12 at either end (only one of which is visible) concentric with a shaft 13 for carrying a blower wheel 14 driven by an electric motor 15 through a drive-pulley 16 and a belt 17 driving a second pulley 19 (shown in Fig. 6) secured to the wheel shaft 13. It is to be understood that the shaft 13 is supported in suitable bearings 18.

As shown in Fig. 6, the blower wheel itself comprises a plurality of vanes 21 secured in a plurality of rings, for example, a pair of rings 22 which are in turn supported upon the shaft 13 by means of spokes 23, shown in perspective in Fig. 1, as extending diagonally from the central portion of the shaft 13 to the rings 22 and carried by a suitable hub. The hub is not shown, as the latter portion of the blower wheel is a conventional construction not constituting a part of my present invention. Preferably, the vane securing rings 22 are spaced from the ends of the vanes 21 in order to avoid interference with the natural streamline flow of air entering the blower housing along the contours of the throats 24.

Although my invention is not limited thereto, to facilitate securing of the vanes within the rings 22 the vanes may be notched as illustrated in Fig. 4, showing one of the vanes 21 provided with four notches 25 arranged in pairs at the positions where the vane is to be engaged by the securing ring 22. Preferably, the vanes 21 are formed of flat sheet metal which has been pressed to the curved form illustrated.

In order to form the vane securing rings 22, a strip 26 of metal is passed through an indexing punch press 27 having a die plate 28 and a punch

28 of such shape as to cut out rabbets 31 illustrated also in Fig. 2. The rabbets 31 are in the form of open arcuate slots, as illustrated more clearly in Fig. 2, tapering from a maximum width at the portion 32 to a minimum width at the portion 33. In addition, the slot 31 is provided with a V-shaped peak 34 to avoid buckling of metal when the slot 31 is closed. Preferably also, in order to assure securement of the vane within the slot 31 after it is closed, shoulder portions 35 are provided in the open slot 31. The taper or difference in breadth of the slot at the portion 33 and 32 is so chosen as to produce the desired degree of curvature in the strip 26 when it is bent to form a ring of the requisite diameter for the blower housing 11.

It will be understood that the sides 36 and 37 of the slot 31 lie along arcs of very nearly the same radii, the difference in radius of parts 36 and 37 corresponding substantially to the thickness of the sheet forming the vane 21 to be secured within the slot 31. The offset of the shoulder portion 35 is also approximately one-half of the intended thickness of the sheet forming the vane 21 in order to form a cloven bridge 38 retaining the vane 21. As illustrated in Fig. 3, the dimensions of various portions of a slot 31 are such that when the strip 26 is bent within its own plane, that is, in a direction parallel to the plane thereof to form a circle or lie along the circumference of a circle, represented by the ring 14, the slot 31 will close upon the waist portion 33 of the vane 21 between the notches 25.

The forming of the ring 22 and assembly of the wheel 14 may be accomplished in any desired manner. Preferably, however, for the sake of speed, economy and accuracy, I employ a bending machine adapted to accomplish precision forming. For example, a machine may be employed such as illustrated in Fig. 7, comprising a strip-supporting roll 41, a pair of retractable-jaw vises 42, a pair of bending dies 43 and a pair of adjustable stops or anvils 44. The dies 43 are mounted in a head adapted to be moved toward the stops 44 by an hydraulic cylinder 45. Each vise 42 is provided with jaws, preferably also actuated hydraulically, for gripping the strips 26 while the dies 43 are bending them against the stops 44, which have a curved die-mating surface 47 conforming in radius to the intended inner radius of the rings 22 in the finished blower wheel. The arrangement is such that both strips 26 are gripped simultaneously as they are bent simultaneously to form the blower wheel. This assures that each strip 26 will be bent to the form lying along the circumference of a circle which lies in the plane of the original straight strip 26. The pressure controls for the hydraulic cylinder 45 are provided with interlocks to prevent actuation until the vise-jaws 42 have gripped the strips 26 firmly. It will be understood that the vanes 21 are to be dropped in the slots 31 as the strip 26 travels along the supporting rolls 41 before the strip reaches the bending die 43. The strip 26 may be chosen of sufficient length to form a complete circumference of the ring 22 or a fraction thereof. After sufficient vanes have been bent into the strip 26 to form a complete blower wheel, the abutting strip ends 48 are joined together in some suitable manner as by riveting or preferably by some fusion process such as welding to form a permanent joint 49, as illustrated in Fig. 8.

In the case of relatively short blower wheels, especially, the rings 22 are preferably pressed to

a form complementary to the inlet throats 24 as illustrated in Fig. 6A. Each ring 22 has the inner portion warped or bent outward to provide a throat 51 flaring out toward the vanes 21.

5 The throat 51 is so curved to an edge 52 that a tangent to the curve at the edge 52 is parallel to the stream-lines of flow of air drawn in through the inlet 24. In this manner a Venturi effect is produced and a maximum amount of air is drawn 10 along the ends of the vanes. The warping of the rings 22 also serves to clinch the vanes 21 in place so as to give additional strength, rigidity and durability to the wheel 14.

15 In the case of conventional double inlet blowers with end rings and radial spokes located at each end the air bypasses approximately fifteen percent of the length of the blade next to each inlet, which means that about thirty percent of the blade length is inoperative due to the solid ring construction. End radial spokes furthermore tend to cut off about ten percent of the air which would otherwise flow into the inlet.

20 In my construction providing a Venturi effect substantially the entire length of blade is active in moving air. By locating the spokes at a distance from the inlet, at the rings 22 the axial air velocity and air flow to the center portion of the blade are reduced so as to allow the ends of the blades to move air.

25 The venturi 51 therefore not only serves to "pocket" a portion of the air in the inlet end of the blade, thereby allowing the ends of the blade to do useful work, but also allows air passing on to the center portion of the blade to reach the 30 blade section adjacent to and touching the venturi. By thus using the spokes as diverting dampers and allowing the ends of the blades to be open, the full length of each blade is utilized. This decreases the internal air velocity to increase 35 the efficiency.

40 The forming of the rings 22 may be accomplished by means of a press having suitable mating die plates, the inner die plate being separable into collapsible parts to permit insertion within the vane assembly and to fit between vanes.

45 My invention is not limited to the form of slot 31 shown in Figs. 2 and 3. As illustrated in Figs. 2a and 3a, a slot 53 may be provided with a heel 54 mating a key 55. This gives a positive lock 50 and will not spread open when the flare is turned on the edge 56. Preferably the slot 53 is so shaped as to leave slight clearances 57 and 58 in the finished ring 22 to compensate for variations in blade thickness and allow the edges 36 and 37 55 to grip the blades 21 solidly.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

60 56 What I claim is:

1. The method of fabricating a blower wheel which comprises the steps of forming a plurality of vanes, punching open arcuate slots in a pair of strips, placing said vanes in successive slots of said strips, each vane having a portion spaced from one end thereof in a slot of one strip and a portion spaced from the other end thereof in a slot of the other strip, bending said strips within the planes thereof to close said slots and 65 secure said vanes simultaneously with curving

said strips along the circumference of a circle, and joining the ends of the strip to form vane-securing rings.

2. In the fabrication of a blower wheel the steps of forming tapered open arcuate slots in a strip, said slots being broader at the open end, placing long narrow sheets, each in one of said slots to form a vane, and bending the strip within its plane along a curve in the plane to close the slots and secure the vanes in position along such a curve.

3. In the fabrication of a blower wheel, the steps of slotting a strip along the edge thereof, with the slots tapering to less width away from the edge of the strip, engaging sheet material with slots in said strip to form vane means, and bending the strip within its plane to close the slots and secure the vane means, whereby the strip is curved to form a circular vane-securing ring.

4. The method of fabricating a blower wheel which comprises the steps of forming a plurality of vanes, punching open tapered arcuate slots in a pair of strips, said slots being broader at the open end, placing said vanes in successive slots of said strips, each vane having a portion spaced from one end thereof in a slot of one strip and a portion spaced from the other end thereof in a slot of the other strip, bending said strips within the planes thereof to close said slots and

secure said vanes simultaneously with curving said strips along the circumference of a circle, and joining the ends of the strip to form vane-securing rings, the amount of taper of the slots in relation to the curvature of the rings being such that the slots are closed upon the vanes.
